A. KLEMTE

FOOTBALL

Original Filed Dec. 21, 1925

FIG. 1

FIG. 2

Inventor:

August Klemte.

UNITED STATES PATENT OFFICE.

AUGUST KLEMTE, OF BREMEN, GERMANY, ASSIGNOR TO GEORG KUEPKER, OF WILHELMSHAVEN, GERMANY.

FOOTBALL.

Original application filed December 21, 1925, Serial No. 76,735, and in Germany November 11, 1924.

Divided and this application filed September 11, 1926. Serial No. 134,868.

This invention relates to an inflatable football of the kind having a cover composed of two hemispherical sections which are connected by means of interlaced lacing loops 5 and recessed at the joint so as to accommodate the lacing and a ring whereby said lacing is covered.

According to the present invention, the sections abut against each other, and lacing loops are connected to both sections so that they can be interlaced cross-wise from staggered positions.

This application is a division of application Serial No. 76,735, filed December 21, 15 1925.

Fig. 1 of the accompanying drawings represents a sectional view across the joint of the football cover, and

Fig. 2, an elevation of the joint showing 20 the lacing.

The cover of an inflatable football is divided into two hemispherical, lined sections a and a' which are connected by lacing and which are contracted at the adjoining edges so as to form, when the sections 25 are united, a circumferential recess. The lacing is situated in the recess and it is subsequently covered by a ring c which fills the recess and lies flush with the ball surface.

According to the invention, the contracted portion is formed by strips e , e' which are secured to and project from under the main cover portion and which are doubled back upon the lining n , as shown in Fig. 1.

For lacing the two cover sections a and a' together, they are provided respectively with lacing loops l and l' . These loops are secured at the edges m between the strips e , e' and the main cover portions.

In assembling the ball, the air bladder is 40 enclosed between the cover sections whereupon the loops l , l' , are interlaced cross-wise from staggered positions as shown in Fig. 2. The loops whereby the lacing is commenced and finished are connected to the air valve of 45 the bladder, as described in application Ser. No. 76735. Finally the ring c is applied to the ball so as to cover the lacing, whereupon the ball is inflated. The inflation causes the ring to be tightened to the recess which 50 holds it in position, and as the lacing is covered by the ring, the inflated ball will present a continuous surface.

I claim:

1. An inflatable football comprising a 55 cover divided into two lined, hemispherical sections which abut against each other and which form at the joint a circumferential recess, lacing loops connected to the sections at the corners of the recess so that they 60 can be interlaced cross-wise from staggered positions for connecting the two sections, and a ring adapted to fill said recess and cover the lacing loops when the ball is 65 inflated.

2. A football according to claim 1 wherein the recessed portions of the sections are formed by means of strips connected to and projecting from under the main cover portions.

3. A football according to claim 1 wherein the recessed portions of the sections are formed by means of strips connected to and projecting from under the main cover portions, said strips being doubled back upon 75 the lining of the sections.

AUGUST KLEMTE.
